MANUALLY OPERABLE TOOL FOR
INSTALLING TUBULAR RIVETSSylvester L. Gookin, Quincy, Mass., assignor to
United Shoe Machinery Corporation, Flemington, N. J., a corporation of New Jersey

Application March 29, 1949, Serial No. 84,016

6 Claims. (Cl. 218—19)

1

This invention relates to a tool for installing tubular rivets. More particularly, the invention pertains to a manually operable riveting tool of the type which acts on a mandrel telescopically related to the rivet to insert and upset the latter from one side of the structure being riveted. While thus intended primarily for blind riveting, it will be understood that this invention may well have other applications.

In the art of blind riveting the installation of a tubular rivet that has been preassembled with a less ductile mandrel is known to have certain advantages. With such assemblages, sometimes referred to as "pop rivets," the practice is to insert the rivet barrel in an aperture of the structure to be pivoted and, while holding a flanged head of the rivet against the structure, to retract the mandrel so that its head upsets the rivet barrel and thereby causes the upset portions to clench the structure tightly. A further characteristic peculiar to pop-riveting is that the mandrel stem, which is ordinarily inexpensive and expendable, is further tensioned after upsetting its rivet and, at a frangible part of the stem, the mandrel is strained beyond its elastic limit and broken. The rivet joint so obtained is rigid, will withstand rather high shearing stress, and, if the mandrel head be securely lodged within the rivet as is the normal case, the joint may be watertight.

Tools have hitherto been provided for installing two-part rivets as just described. A difficulty commonly met with in using many of these tools effectively, however, has been that where the mandrel gripping and pulling power has been adequate, their weight and complexity have been such as severely to detract from their maneuverability. On the other hand, other tools reduced in weight and intended for manual operation have afforded maneuverability but lacked the requisite capacity easily to break and dispose of the mandrel stem.

In view of the above circumstances the chief object of the present invention is to provide an improved hand tool for installing rivets of the aforesaid character, which tool shall be simple in construction and operation, easily manipulated and yet capable of setting such rivets and then breaking and ejecting their respective mandrel stems in work strokes requiring the expenditure of a minimum of effort.

With this object in view, one feature of the invention is the provision of an operating hand lever for retracting the main body of the tool from its anvil, and novel mandrel gripping mechanism constituting a self-contained unit within

2

said body and responsive to said lever for first gripping and thereafter tensioning the mandrel. Advantageously, actuation of the mechanism for gripping does not depend on appliances or fastenings outside the tool body and also the lever is effective to enhance the gripping power of the mechanism as the tension increases.

A further feature of the invention resides in the provision of means for automatically releasing and ejecting the broken mandrel stem from the tool after the end of an operating stroke, said means comprising mechanism for momentarily restraining a mandrel gripping jaw in inoperative position at the end of said stroke so as to enable an energized element forcibly to expel the broken mandrel stem from the tool.

The above and other features of the invention will now be described in more detail with reference to its embodiment in a tool shown in the attached drawings, in which

Fig. 1 is an elevational view of the riveting tool exemplifying this invention, extremities of the operating lever (shown in initial position) and main body being broken away;

Fig. 2 is an elevational view of most of the tool shown in Fig. 1, but turned 90° about its longitudinal axis;

Fig. 3 is a partly sectional and partly elevational view of the tool on an enlarged scale and as seen in Fig. 2 but having its elements in their initial positions prior to riveting a structure;

Fig. 4 is a view similar to Fig. 3 and illustrating the same tool with its parts in a subsequent operating stage, namely, the instant after the mandrel stem has been broken;

Fig. 5 is a view similar to Fig. 4 but showing the next stage of operation, namely, ejection of the broken mandrel;

Fig. 6 is a section taken along the line VI—VI of Fig. 3, the mandrel being omitted; and

Fig. 7 is a view in perspective of one of the mandrel gripping jaws (in initial position) and elements associated therewith for restraining it in inoperative position.

The main body of the tool is comprised of a slender barrel 10 that is provided with a longitudinally extending kerf of gradually increasing depth for accommodating a pair of toggle arms 12, 14 (Figs. 1 and 2). The toggle arm 14 is mounted on a pin 16 which is received by a boss 18 on a rearward part of the barrel 10. The knee of the toggle is pivotally connected by a U-shaped link 20 to a hand lever 22. Opposite cheeks of the lever 22 are fulcrumed on pins 24, 26 secured in protuberant portions 26, 26 of the

barrel 10. The purpose of the lever 22 is to afford means for manually applying force via the aforesaid main body so as to operate the tool as will be subsequently described.

The barrel 10, solid rearwardly of the boss 18, becomes tubular as its kerf extends forwardly to receive an end of the toggle arm 12 (Figs. 3 and 4). This tubular portion of the barrel is provided with a slidable crosshead 28 and, for a purpose hereinafter explained, with a compression spring 30 bearing thereon. The crosshead 28 is connected to that end of the toggle arm 12 by a pivot pin 32. A cross pin 34 projects through opposing slots 36 extending longitudinally of the barrel 10 and also projects through corresponding holes in the crosshead 28 and an external sleeve 38 into which it is screwed. This sleeve 38 and a hollow but rigid member 40 are threaded together endwise to comprise an anvil portion 42 of the tool. A collar 44 is driven into the threaded end of the member 40 to brace it radially. The other end of the member 40 has a flat external anvil face 46 for bracing the rivet against retraction of the mandrel head and an internal face 48 which will be referred to hereinafter. From the construction just described it will be appreciated that the main body or barrel 10 is telescopically related to the anvil portion 42 of the tool.

The main body of the tool is also comprised of an extension member 50 firmly anchored by a pin 52 to the barrel 10. It is this extension portion 50 of the main tool body which has the mandrel gripping mechanism arranged as a self-contained unit within it and is in telescopic engagement with the member 40. One end of the member 50 is engaged by the spring 30. A substantially central bore 54 (Figs. 3, 4 and 5) in the member 50 is coaxial with an aperture 55 in the anvil face 46, the bore 54 and aperture 55 being of diameters freely to receive the shank or stem of a nail-like mandrel 58. An ejection device in the form of a spring-backed plunger 60 engageable with the mandrel stem is seated in an enlarged inner end of the bore 54.

Fig. 3 illustrates the preassembled mandrel 58 in its more ductile tubular rivet 62 and in initial position relative to the tool and a structure S. It may be noted that the flange of the rivet is braced by the anvil face 46 while a mandrel head 64 (which has been thrust with the unset rivet through a hole in the structure S from the accessible tool-side thereof) is adjacent to the headless end of the rivet barrel. A constriction 66 is normally arranged in the mandrel stem just below the head 64.

The self-contained mechanism by which the mandrel 58 is first gripped and thereafter pulled rearward to set the rivet 62 as seen in Fig. 4 comprises a pair of independently movable jaws 68 and 70 supported in the member 50 and arranged to have their respective mandrel gripping surfaces 72, 74 extending in the bore 54. The surfaces 72, 74 are generally flat and provided with serrations extending transversely of shallow but straight grooves formed therein. Together the jaws 68, 70 are thus adapted to receive and clamp the mandrel stem. The jaw 68 is guidably mounted in a keyway 76 formed to maintain the groove in the surface 72 in parallel relation to the axes of the mandrel and the bore 54. The jaw 70, on the other hand, has a socket 78 for receiving one end of a toggle element in the form of a ball-ended flat link 80, the other end of the link 80 being nested in a socket 82 formed in a yoke por-

tion 84 integral with the member 50 and having a shoulder 85 (Fig. 3).

It should be noted that the link 80 and its pivot sockets 78 and 82 lie in a general plane disposed at an angle to the axis of the mandrel 58, which plane intersects the gripping surface 74 about midway of its length. It will further be seen that this pivotal suspension of the jaw 70 enables it to be swung longitudinally of the tool and transversely of the bore 54 for cooperative mandrel gripping relation to the jaw 68. For a purpose hereinafter explained, a pin-like projecting portion 86 of the jaw 70 extends freely through a bore in the forward end of the member 50 and normally, i.e., when the tool is in initial operating position, is engageable endwise with the face 48. Bearing on a rearward part of the jaw 70 is a small compression spring 88 mounted in the yoke 84 yieldingly to urge the rearward part of the jaw 70 toward the jaw 68.

Mandrel releasing mechanism, also associated with the jaw 70, comprises (Figs. 6 and 7) a rack 90 pivoted on a fulcrum pin 92 secured in a boss on the member 40, a triangular pawl 94 mounted on the link 80 for cooperating with the rack 90, and a compression spring 96 inserted in a bore of the member 40 for yieldingly urging said rack into position for engagement with the pawl 94. The spring 96 bears on one side of a step 98 of the rack and the other side of the step 98 is engageable with a stop screw 100 threaded into the member 40. The stop screw 100 provides a convenient means for adjusting an inclined cam face 102 (Fig. 7) of the rack 90 heightwise relatively to the pawl 94 and thereby compensates for wear in the elements as well as allows for different diameters of mandrels to be properly acted upon.

In preparing to operate the tool the stem of the mandrel 58 is first thrust into the alined aperture 56 and bore 54 until the rivet 62 engages the anvil face 46. At this time the hand lever 22 will, under the influence of the spring 30, have been positioned as seen in Fig. 1. Accordingly, the projecting portion 86 of the jaw 70 may then engage the face 48 to prevent the spring 88 from giving to the link 80 an initial position so near to dead center as to make difficult the initial spreading movement of jaw 70 by the stem 58. Rearward insertion of the mandrel between the jaws 68 and 70 causes it to engage and load the spring-backed plunger 60 (Fig. 3) for subsequent ejection action as will be seen. The spring 88 is then yieldingly urging a rearward portion of the mandrel gripping surface 74 toward contact with the surface 72. The unset rivet and its mandrel are thereby retained in ready position in the tool so that operation may be commenced whenever convenient, and even though the tool is to be manipulated or operated with its anvil portion 42 directed downwardly.

For the sake of clarity and simplicity in describing relative operating movements of the tool elements it will hereinafter be assumed that the anvil portion 42 remains stationary.

Having placed the loaded tool with the rivet 62 and mandrel 58 projecting through a structure S, as seen in Fig. 3, to set the rivet as shown in Fig. 4 the operator may with one hand swing the lever 22 toward the main body of the tool and in the direction of the arrow A (Fig. 1). Such movement of the lever 22 serves to spread the toggle arms 12 and 14, thereby retracting the main body of the tool, including the member 50, to move it rearwardly of the anvil portion 42.

Thus on analysis, it may be considered that, since the anvil portion 42 requires the cross pin 34 and crosshead 28 to remain stationary, the pivot pin 32 is prevented from moving toward the structure S and the toggle spreading must result in the force acting through the boss 18 to urge the main body and member 50 rearwardly.

The first result of such rearward movement of the member 50 is to increase the relatively light initial mandril gripping pressure effected by the spring 88 by means of the pivotal movement of the link 80 in its sockets 78 and 82. It may be noted that had the link 80 initially been disposed more nearly perpendicular to the mandril 58 the tool would be less able to accommodate mandrils with different diameters and the "bite" of the jaw 70 might not have been adequate. Similarly, had the link 80 initially been disposed in more nearly parallel relation to the mandril 58 some tendency for slippage of the mandril gripping surface 74 might be expected. The arrangement, however, is preferably such that the link 80 is inclined away from said parallel relation more than 45° and acts as one arm of a toggle mechanism in which the jaw 70 serves as the other arm and the socket 78 is the knee. Retraction of the member 50 tends to straighten the toggle arrangement so that the jaw serrations are well embedded in the mandril stem before they start rearward movement as a unit with the member 50. The jaw 70 does not slip on the mandril but instead, as the link 80 is forced by retraction of the member 50 to assume a more nearly perpendicular position relatively to the mandril, the latter is more firmly clamped and gripped between the grooves of the jaw surfaces 72, 74. Continued effective mandril gripping action by these surfaces is attained because tensioning occurs in each instance only when the mandril stem has first been securely gripped and then, when the jaws move longitudinally of the member 50, they are ordinarily retracted in unison. Filling and, in effect, smoothing of the groove serrations with scraped off mandril material is accordingly avoided in the present tool.

The early part of the operating stroke succeeds in drawing the mandril head 64 into the rivet barrel to upset the rivet 62 as seen in Fig. 4. As the lever 22 is thereafter swung further on its fulcra 24, 24 to complete the installation its mechanical advantage increases and, although much greater power is required to strain and break the mandril stem, no great increase in effort is required to be exerted on the lever.

When the rivet 62 has been upset the mandril gripping mechanism is further retracted with the member 50 to strain and then break the mandril at the constriction 66. Normally at the instant of breaking, the lever 22 will not have quite reached its most rearward position but the pawl 94 will be nearing or engaging the cam face 102. After the mandril is broken, its stem may be easily released from the clamping bite of the surfaces 72 and 74, the particular manner and instant of release depending on the adjustment of, and tolerances in, the tool, and possibly the size of the mandril and the rapidity with which the lever 22 is swung. As will be described, the jaw 70 may be separated from the jaw 68 to effect mandril release during the further and final rearward movement of the lever 22, but more likely such separation and release will be caused by the subsequent return of the lever 22 to initial position by its movement counter to the direction indicated by the arrow A (Fig. 1). Completing 75

the rearward stroke of the lever 22 causes the pawl 94 to ride upwardly on the inclined cam face 102 either to cause the toothed surface 74 to be lifted relative to the mandril stem or to cause pivoting of the rack 90 against the spring 96 and the pawl 94 to move beyond the cam face 102 and become engaged with teeth 89 on the rack 90 as the latter is yieldingly urged against the pawl by the spring 96. If mandril release was not effected when the pawl 94 moved rearwardly up the inclined cam face 102 or up the inclined surface of one of the teeth of the rack 90, lever 22 is returned, preferably rapidly, i. e. moved forwardly or counter to the direction of arrow A. During the initial part of this return stroke, pawl 94 moves across the rear inclined faces of the teeth 89 either to pivot said rack against the pressure of spring 96 without releasing jaw 70, or to cause the pawl 94 to ride up one of said rear faces of the teeth whereupon the link 80 will be pivoted in its socket 82 counter-clockwise as viewed in Fig. 7 (clockwise as viewed in Fig. 4) and the jaw 70 may consequently be raised sufficiently in the bore 54 to obtain mandril release. Should the jaw 70 still grip the mandril stem, its release will be positively effected by continuing the return stroke of the lever 22. Such further forward movement of the lever moves the member 50 forwardly with the link 80 and the jaw 70 until forward movement of the latter is stopped by the pin 86 striking the wall 48. The impact of the pin upon the wall arrests such movement of the jaw 70 relative to the wall 48. Continued forward movement of member 50 effects a clockwise movement of link 80 (as viewed in Fig. 4) above pivot 82 thereby shifting jaw 70 toward yoke 84 against the resistance of the spring 88 to loosen the grip of the surface 74 from the mandril.

Upon operation of the mandril release mechanism in any of the ways indicated the plunger 60 exerts sufficient force on the end of the mandril stem to effect ejection. The tool is then unloaded and ready for making the next installation. If a rivet barrel 62 of different length is to be upset the member 40 will be threaded in or out of the sleeve 38 suitably to adjust for the extent of endwise rivet collapsing desired.

Having thus described my invention what I claim as new and desire to secure by Letters Patent of the United States is:

1. In a riveting tool of the type in which an anvil portion braces a tubular rivet against the upsetting movement of a mandril, a main body arranged for movement relative to said anvil portion, cooperative mandril gripping jaws within said body and individually movable lengthwise thereof, only one of said jaws having a pivotal connection with the body by which to swing into and out of mandril gripping relation, and means for retracting the body from said anvil portion, said retracting means being effective through said pivotal connection to cause said one jaw to cooperate in gripping and tensioning the mandril.

2. A manually operable tool for installing a tubular rivet by means of an upsetting mandril comprising an anvil portion for bracing the rivet against retraction of said mandril, a main body arranged for movement toward and from said anvil portion and having a bore substantially coaxial therewith for receiving the stem of said mandril, means for retracting the main body from the anvil portion, cooperative jaws arranged and individually supported within the main body

for gripping and retracting the mandril stem in said bore, and a link pivotally connecting one of said jaws to the body for effecting movement of said one jaw along said bore and into gripping relation with another of said jaws during operation of said means.

3. In a riveting tool of the type in which an anvil portion braces a tubular rivet against the upsetting movement of a mandril, a main body arranged for movement relative to said anvil portion and provided with an axial bore for receiving the stem of said mandril, cooperative jaws movably mounted in said body and disposed lengthwise of said bore for gripping the stem therein, a pivotal element intermediate the body and one of said jaws for controlling the mandril gripping relation of the latter, and means for retracting the main body from said anvil portion whereby the pivotal element is actuated to close said jaw by toggle action therewith.

4. A manually operable tool for installing a tubular rivet by means of an upsetting mandril comprising an anvil portion adapted for engagement with an end of the rivet, a main body arranged for telescopic movement with respect to said anvil portion, means mounted on the body for moving the latter relatively to the anvil portion, a pair of mandril gripping jaws supported in said body for cooperative movement longitudinally thereof, means pivotally mounted in the body for swinging one of said jaws into mandril gripping relation when the body is retracted from the anvil portion to tension the mandril stem, and a mechanism thereafter cooperative with said pivotal means to restrain one of said jaws in an inoperative position whereby said mandril stem is released for ejection.

5. A riveting tool comprising an anvil portion for bracing a tubular rivet against the upsetting movement of a mandril, a main body arranged for movement relative to said anvil portion, man-

5

10

15

20

25

drill gripping mechanism entirely within said body and including a pair of cooperative jaws, one of said jaws being movable in a linear path longitudinally of the tool only and the other being pivotally connected to a member bearing angularly on the body, said other jaw being thus constrained for movement toward the anvil portion in a curve converging with said path, and means for retracting said body from said anvil portion, said body and member constituting a toggle for effecting convergence of said jaws.

6. A tool for installing tubular rivets comprising an anvil portion for bracing a rivet against retraction of an upsetting mandril, a body retractable from said anvil portion, means for so moving the body, mechanism within the body operable by retraction thereof to grip the stem of the mandril, said gripping mechanism including a pair of cooperating jaws normally individually movable in paths extending longitudinally of the tool, and a pivotal member actuated by said means and disposed angularly between said body and one of said jaws for restraining the movement of said one jaw to a curve converging with the path of the other.
